ATTY

UNITED STATES PATENT OFFICE.

JOHN REID, OF NEW YORK, N. Y.

FURNACE-FRONT FLAREWAY.

1,332,005.

Specification of Letters Patent. Patented Feb. 24, 1920.

Application filed April 19, 1919. Serial No. 291,361.

To all whom it may concern:

Be it known that I, JOHN REID, a subject of the King of Great Britain, and residing at 30 Church street, in the city of New York, 5 in the State of New York, in the United States of America, have invented a new and useful Furnace-Front Flareway, of which the following is the specification.

The invention relates to improvements in 10 furnace front ash pit flareway, as described in the present specification and illustrated in the accompanying drawings that form part of the same.

The invention consists essentially of the 15 novel formation rigid with the inner wall of the furnace front, whereby an unobstructed way in the form of a ramp is furnished for the withdrawal of the ashes across the division between the front and the pit and up to 20 the level of the ash pit flare.

The objects of the invention are to insure a good joint between the ash pit flare and the pit, so that the work of the fireman in removing the ashes shall be greatly facilitated; 25 to further my work in the standardization of furnace fronts, particularly for marine installations, though in many cases suitable for stationary plants, and in this connection to make it unnecessary to slope the flare for the 30 different constructions of furnace, but instead merely alter the shape or size of the lip forming the way; and generally to provide in a furnace front a substantial addition, that will not make any material difference in the cost for itself and at the same 35 time reduce the expense and remove the trouble and inconveniences incident to the fitting of ash pit flares to the pit mouth.

In the drawings, Figure 1 is a perspective 40 view of the lower portion of a furnace front showing the ramp leading to the flare.

Fig. 2 is a cross sectional view through the front and back plate, showing the flare and flareway.

Fig. 3 is a cross sectional view showing a modified form of flareway.

Fig. 4 is a vertical sectional view through the major portion of the furnace front.

Like numerals of reference indicate corresponding parts in each figure.

Referring to the drawings, the numeral 1 indicates the ramp or way, which in length is approximately the width of the ash opening in the back plate 2 and preferably forms

part with said back plate or any part rigid 55 therewith and slopes from the flare 3 joining the front plate 4 and back plate 2 at the ash openings 5 and 6.

It will thus be seen that the back plate casting has a ramp cast onto it. This ramp 60 is proportioned to meet the requirements, that is to say, the distance from the level of the ashpit flare to the bed of the pit. In consequence of this construction the casting may be made with only minor changes to 65 suit the various installations, whereby the interchangeability is greatly facilitated and the adoption of this flareway justified. All the flares can be at the same level and horizontal in a lot of furnace fronts and the 70 ramps made to suit the level of each one in relation to the pit bed. This effects great economy in patterns and in casting operations and contributes largely in standardizing many parts of the front, so that they 75 may be stocked up and furnished to the customer immediately or as spare parts for an equipment already installed.

In Fig. 3 the ramp 8 is shown as filling in and bridging the space between the back 80 plate 9, and the furnace mouth plate 10 and is therefore to all intents and purposes in this form a thickening of the flange 11 for the width of the ash pit opening, the upper side 12 of this flange sloping to the opening 85 on a level with the edge thereof and the upper surface of the flare 13. In this construction the furnace mouth plate 10 is turned outwardly.

In the use of the front formed with this 90 invention, the ashes are drawn out of the pit by a fire iron of any suitable type and in drawing the ashes along, the scraper iron pulls them over the ramp onto the flare and so on out of the opening through the front 95 plate.

The necessity of having the flare slope downwardly to meet the furnace mouth is thus eliminated and further the difficulty incident to making a good free way for the 100 ashes is entirely done away with and a good path provided, which will of course facilitate the work of the fireman.

The exact forms of the invention herein described and illustrated will not necessarily 105 be closely adhered to, so various changes may be made without departing from the spirit of the invention and the protection herein

granted shall not be invalidated if such changes remain within the scope of the claims for novelty following.

What I claim is:—

- 5 1. In a furnace front, a front plate and a back plate having an ash opening communicating with the ash pit of the furnace, and a ramp rigid with the said back plate and having an upper surface sloping downward and inwardly from the ash opening to substantially the floor of the ash pit.
- 10 2. In a furnace front, a front plate having an ash opening, a back plate also provided with an ash opening, a flare extending from the opening of the front plate to the opening of the back plate, and a ramp rigid with the said back plate and located at the

bottom of the ash opening and extending downwardly and inwardly to substantially the floor of the ash pit of the furnace.

20

- 25 3. In a furnace front, a front plate and a back plate both having ash openings, a flare bridging the space between said openings, and a ramp extending downwardly and inwardly from the back plate to substantially the floor of the ash pit of the furnace and flush at its higher end with said flare, said ramp being cast integral with the back plate and forming therewith a recess located at the under side of the ramp between the same 30 and the back plate.

Signed at the city of New York this 7 day of April, 1919.

JOHN REID.
